EASEL BOOK CONSTRUCTION FOR RING
BOOKS OR LOOSE-LEAF BINDERSFrank Stanley Schade, Holyoke, Mass., assignor
to National Blank Book Company, Holyoke,
Mass., a corporation of Massachusetts

Application July 30, 1947, Serial No. 764,722

2 Claims. (Cl. 281—33)

1

This invention relates to an easel book construction for a ring book or loose leaf binder. In the prior art there are many forms of books incorporating easel supports on their binder constructions. The novelty in the present case relates to the way the easel is made to cooperate with the metal part of the ring book.

The object of the invention is to make a more efficient ring binder and easel construction, with respect to the low cost of building in the easel element and to the specific way it works to make the structure more satisfactory from both the manufacturer's and user's standpoint.

An example of the way to practice the invention is disclosed by the drawings and their description. The example was made for a loose leaf cook book. It is used most conveniently when a housewife is most likely to have both hands occupied in her cooking work and when an easel cook book is the most useful kind.

In the drawings:

Fig. 1 is a perspective view of the binder provided with the easel in position for use;

Fig. 2 is a longitudinal section along the rivet line of the back panel but with the metal structure generally not sectioned;

Fig. 3 is a view of the easel part of the structure separate from its binder part; and

Fig. 4 is a view looking at the back of the binder as it appears with the easel folded against the back panel.

In the example shown, the binder consists of the curved back panel 1, covers 2 and 3 with hinges 6 along the sides of the back panel, the ring binder "metal" 4, riveted at 7 to the back panel. So far the structure is a routine type of three ring binder. To this type of binder shown there is added the easel 5. It is shown separately from the binder in Fig. 3.

A sheet metal plate 8 in single piece form is made with a lower portion 20, upstanding ears 21, a wider portion 22, an upstanding end flange 23, and with spaced hinge eyes 24 on the upper edge of said flange. The portions 20 and 22 are curved to fit snugly against the upper portion and on the inside of back panel 1. In this position portion 20 is overlapped by the end portion of the ring binder "metal" 4, see Figs. 1 and 2, in the assembly to be referred to later. Portion 20 is of the same width as "metal" 4. The latter also extends upwardly a little to overlap a part of the wider portion 22, see Fig. 1. The ears 21 are bent in from opposite sides to clinch over the edges of the binder "metal" 4. In assembled position a hole 9 in portion 20 coincides with

upper rivet 7 used to fasten the "metal" 4 to back panel 1. Also in assembled position the flange portion 23 is upstanding at right angles. Its lower edge is curved as portions 20 and 22 are to conform to the curved back panel, but flange 23 is in a right angle plane to the plane of the book covers. The single upper rivet 7, in fastening one end of "metal" 4 to back panel 1, also fastens the sheet metal plate or stamping on the back panel as indicated in Fig. 2. When ears 21 closely confine "metal" 4, see Fig. 1, the metal stamping is held against any pivoting movement on the upper rivet 7.

The easel arm is made of one piece of wire bent into general U form. Its connecting portion 11 is curved to conform to curved back panel 1. Its legs 12 are spaced by portion 11 to lie generally along the spaced hinges 6, preferably just inside the hinge lines. At the top of legs 12 the wires are bent into parallel short portions 13, then inwardly on the axis of hinge eyes 24, see Fig. 3, and then into downwardly bent portions 14.

The preferred angles of these bends are indicated in Figs. 2 and 3. They determine the angle at which legs 12 can be turned away from the back panel before portions 14 will be stopped by contact with the inner side of flange 23. This angle of turning will determine the incline of the easel when the binder is put in the position of Fig. 1. The wire mentioned is stiff and is bent by tools at the factory.

From what has been said, it will be seen that the factory cost of supplying the easel to a three-ring binder is a low cost. The single sheet metal stamping and the single piece of stiff wire are all that is needed for the material of the easel. This small amount of material is shaped as shown in the drawings and as described above to make a specifically fine self-effacing and efficient easel which combines with the binder with these advantages. The appearance of the book is almost identical with or without the easel. That is to say, the easel construction has such a self-effacing characteristic that the book user is hardly conscious except by the function performed that a complete easel construction is built into the book. The wire legs 12 fold against the hinge lines 6 to be inconspicuous and only the portion 11 connecting the legs vary the lines of binder construction. Yet when the easel arm 5 is put in book supporting position, Fig. 1, the easel gives very efficient support directly from the "metal" back bone of the binder. It is one which will not get out of order under hard usage in public use.

In manufacture it should be noted that the metal parts shown in Fig. 3 can be made and assembled as easel parts. When any routine binder of the type shown as the ring binder element needs an easel, the manufacturer can merely attach the assembly of Fig. 3 when he attaches the "metal" 4 to the back panel. The "metal" parts of the easel combine with the "metal" parts of the binder to supplement one another while the binder case, back panel and hinged covers are of the same construction with or without the easel added.

The way to combine the easel and the ring binder will benefit the manufacturer and the user.

Having disclosed the invention, what is claimed is:

1. A ring binder of the kind having a back panel, two hinged flat hard covers, and metal parts of rings and operating mechanism therefor, including a cover plate extending along and riveted to the back panel in the usual fashion, said structure being combined with an easel of the following structure and also riveted to the back panel, said easel comprising a single piece of sheet metal stamping to support the easel arm and having a tongue resting solidly against the inside of the back panel to underlie the top end portion of the cover plate and over an area including the rivet hole near the upper end of the panel, two side ears on said tongue closely confining the side edges of the cover plate, and outwardly of the rivet position, said stamping extending outwardly from said side ears to the end edge of the back panel and there bent upwardly to extend a short distance at a right angle relation to said back panel, the upper portion of the bent up portion being curled into two hinge eyes whose axes are parallel to the top edges of the covers when they are wide open in the same plane, an easel arm comprising a single piece of stiff wire generally U-shaped having end portions in 40

angular parallel relation for a short distance and then bent at right angles to extend through the hinge eyes of the one piece stamping and again bent at right angles and in parallel relation to act as stops against the said bent up portion of said stamping, whereby the U-shaped portion of the easel arm may lie inconspicuously against the back panel when the easel is hinged to inoperative position and the upper bent portions of the easel wire may run inconspicuously over the top edge of the back panel adjacent their spaced corners, extend inwardly through said hinge eyes and the very ends or said stop portions are hidden back of the end portion of said one piece stamping.

2. A ring binder of the kind having a back panel, hinged covers, and ring mechanism lying along and on the inside face of the back panel, with rivets fastening it near the ends and added to said ring binder an easel construction comprising a hinge plate of sheet metal having a portion extending across the upper margin of the back panel against its inside face and extending down far enough to be riveted to the back panel with one of the said rivets fastening said ring mechanism, side ears in the hinge plate extending against said mechanism to prevent the plate pivoting on said rivet, an upstanding flange at the upper end of said plate having hinge eyes bent at the upper edge of the flange, a stiff wire having bent ends passing through said eyes to hinge the wire on said flange, said ends having bent extensions to serve as hinge stops by abutment against the inside face of said flange, said wire being bent into an easel arm by extension to and down along the side edges of the back panel on the outside.
